UNITED STATES PATENT OFFICE.

J ARTHUR MINCH, OF TOLEDO, OHIO.

TIME CARD.

Application filed April 14, 1920. Serial No. 373,683.

To all whom it may concern:

Be it known that I, J ARTHUR MINCH, a citizen of the United States, residing at Toledo, in the county of Lucas and State 5 of Ohio, have invented certain new and useful Improvements in Time Cards, of which I declare the following to be a full, clear, and exact description.

This invention relates to employees' daily 10 time cards and is particularly adapted for use in connection with cost accounting systems.

An object of my invention is to provide a record card of convenient size for each 15 workman upon which all the necessary data may be written or printed in columns and spaces provided therefor to comprise a complete account of the various jobs making up his day's work.

20 Another object is to provide a card of this nature for each day of the week, each card having a tab upon which may be written a total of items of a similar nature appearing on the card, the tabs of the successive 25 days of the week being arranged to show one beside the other to thereby enable a convenient and rapid summation for the entire week.

Further objects of this invention relate 30 to economies of manufacture and details of construction as will hereinafter appear from the detailed description to follow. I accomplish the objects of my invention in one instance by the devices and means described 35 in the following specification, but it is evident that the same may be varied widely without departing from the scope of the invention as pointed out in the appended claims. A structure constituting one embodiment of my invention, which may be the preferred, is illustrated in the accompanying drawings forming a part thereof, in which:

The single figure of the drawing represents 40 a series of cards and carbon duplicates, the top card with its duplicate being turned down to expose to view the card of the succeeding day.

The top card 5 of the series is shown 45 having vertical lines 6 dividing it into columns and horizontal lines 7 dividing these columns into spaces, also other horizontal lines 8 at the top of the card to form appropriate heading spaces. Certain of the 55 spaces formed by the intersection of the vertical and horizontal lines are shown subdivi-

vided by other vertical and horizontal lines. In the case of the column at the left hand side of the card which is designated, "Assignment" the subdivisions include items 60 such as "Operation No.," "Quantity of pieces finished," "Order No.," "Day rate" and "P. W. rate." The "assignment" column is shown divided in five identical sections for use in recording data relating to 65 five different jobs. In the central portion of the card opposite each of the "assignment" sections is a section upon which is stamped a clock record showing the length of time 70 in hours and tenths of an hour during which the employee was engaged at each particular job. To the right of the clock record are other spaces, which, as shown, include such as "Piece work O. K.," "Elapsed time," "Am't. earned" and "Order posted." 75 Across the top of the card is shown the employee's number, name, department number and the date.

At the right hand side of each card there is shown a tab which, if desired, may be folded back temporarily for the sake of convenience in handling the card. The card for use on the first day of the week, which, in the particular case, illustrated, is Thursday, has a tab 10 of minimum length; the 80 next card, marked "Friday" has a similar tab 11 but of approximately twice the length, while the following card has a tab of approximately three times the length of the first card, and so on through the series. 85 Thus each card of the series is provided with a tab and the length of the tab of each succeeding card is longer by a uniform amount than the preceding card. The exposed portion of each tab is shown designated with the day of the week and as having two columns, one for receiving the total number of hours worked on that day and the other for receiving the total amount 90 earned that day. It will be noted that the 95 tab 13 of the last card of the series, in the case illustrated, the "Wednesday" card, is given additional length in order to provide a space in which may be recorded the total number of hours worked and the total amount earned for the week. The lower portion of this tab is accordingly shown with the designation "Total," "Hrs.," and "Amt." If desired for the purpose of obtaining a duplicate record, a duplicate card 100 105 110 115 may be provided for each day and suitable well known means provided for dupli-

cating the record on this card as for example by inserting between the two cards a sheet of carbon paper or by coating the back of the original card with carbon. The 5 duplicate card, being for reference purpose only, is illustrated as devoid of a tab.

The manner of using cards such as described above is as follows: The workman at the beginning of the day is provided with

- 10 a suitable card for that day bearing his number, name, department number and date. Appropriate data may also be entered in the lower assignment space relating to the first job of the day. The card is inserted in a suitable machine which prints at the bottom of the card a record 16 showing the time he began work. In this instance he reported for work on time, namely at the zero hour, at which time he began work on order number "996." Simultaneously with the stamping of the clock record a narrow strip 18 is cut from the lower left hand edge, the purpose of which is to limit the distance the card may drop in the machine for the next record, as is well known with machines of this type. At the completion of the first job and the beginning of the second, the workman again inserts his card in the machine and makes a second time record, the successive records being properly imprinted in the spaces provided therefor. Thus at the completion of the day, the exact time at which the workman began his day's work and the exact 30 number of hours and fractions thereof which he worked at each job or order may be found by simply reading the clock records. For example, he worked at the first job 2.5 hours, on the second job three hours, etc.
- 35 From the clock records thus obtained the amount earned on each job is computed and entered in the appropriate space while the total number of hours and the total amount earned for the day is entered on the tab.
- 40 At the end of the week the cards for the entire week are gathered together being arranged in order and the daily totals of hours and amounts earned, which it is to be noted are now arranged in a column convenient for adding, are summed up and the grand totals for the week entered in the appropriate spaces on the last tab. The above arrangement results not only in great convenience to the foreman and the workman as well as obtaining an exact record of data necessary to the computation of the workman's wages and the cost of articles manufactured but an immense amount of labor is saved in gathering together and summing up the individual items from which are calculated the workman's weekly wages and the total number of hours per week he worked.
- 45 The card illustrated shows an inverted time impression 20 at the top which was made when the workman "rang in" after

the noon lunch period. It might be mentioned that an allowance for the noon lunch period is provided for by stopping the time printing machine during that period.

It will, of course, be understood that it is not essential to the invention that the tabs be of the particular size and shape illustrated or that they be located along the right hand edges of the cards. Indeed, they may be of any desired size and shape 75 and be attached to any one of the four sides of the cards so long as the items they carry appear in order to facilitate computation when the cards are properly arranged.

Inasmuch as the invention herein disclosed is susceptible of various other embodiments and as various changes might be made in the embodiment set forth, it is to be understood that all matter described above or shown in the accompanying drawing is to be interpreted as illustrative only and not in a limiting sense.

Having thus described my invention, what I claim as new and desire to secure by Letters Patent, is:

1. A time card for use in cost accounting systems having lines dividing it into sections appropriately designated for receiving data relating to each of a plurality of jobs and having a tab attached to the side 95 thereof designated to receive a total of items of a similar nature appearing in the said sections and adapted to be positioned adjacent the tabs on similar cards.

2. A series of time cards for use in cost accounting systems each having lines dividing it into sections appropriately designated for receiving data relating to each of a plurality of jobs and each having a tab attached at the same side thereof adapted to receive a total of items appearing in said sections, the tab portion of each successive card of the series appearing below the tab of the preceding card whereby the items appearing on the tabs are arranged in a 100 row or column.

3. A series of time cards arranged in book form for use in cost accounting systems each having lines dividing it into sections appropriately designated for receiving data relating to each of a plurality of jobs and each having a tab attached to the same side thereof designated to receive a total of items of a similar nature appearing in said sections, the tab of each succeeding card from the first to the last being progressively longer than the preceding tab whereby items of a similar nature appearing on said tabs are arranged in columns when the cards are superposed and the summation of 115 said items thereby facilitated.

In testimony whereof, I affix my signature.

J ARTHUR MINCH.
